WILLIAM J. VINCENT, OF ROCHESTER, NEW YORK, ASSIGNOR TO THE ROCHESTER TELEPHONE CORPORATION, OF ROCHESTER, NEW YORK, A CORPORATION OF NEW YORK

TELEPHONE SYSTEM

Application filed May 5, 1930. Serial No. 450,047.

This invention relates to telephone systems and more particularly to manual telephone systems.

In the past it has been the practice in manual telephone systems, especially in the case where the busy called line terminated in the same exchange as the calling telephone line, to provide at least one busyback jack into which the operator plugged the calling end of a cord circuit connected to a calling telephone line which desired connection to a called line that tested busy. As long as this cord circuit was connected to such a busyback jack, a source of the busy tone current was extended to the calling telephone line which caused a distinctive signal in the receiver of the calling telephone line to indicate to the subscriber thereat that the wanted line was busy. In such a system it was necessary for the operator to insert the calling plug of such a cord circuit into a busyback jack and subsequently to remove the plug from that jack when it was desired to terminate the busyback signal. These operations required a considerable amount of time which otherwise could be used in establishing useful connections.

In accordance with the present invention the need for busyback jacks has been obviated by providing a busyback key and associated equipment common to all of the cord circuits of an operator's position so that as soon as a called line tests busy it is merely necessary for the operator to depress this key after which the busyback signal is transmitted to the calling telephone line until the subscriber abandons the call or initiates a recall. A further feature of the invention includes the use of the ringing relay of a cord circuit to control the application of the busyback tone to the calling telephone line. These and other features will appear from the detailed description and appended claims.

For a clearer understanding of the invention reference is made to the drawings in which with Fig. 1, placed above Fig. 2, there is diagrammatically represented a telephone system utilizing the present invention. In the upper left hand corner of Fig. 1 there is represented one of a plurality of telephone

lines which may be a calling line while the center portion of this figure and a portion of Fig. 2 above the broken line represent equipment individual to a cord circuit of which there may be several located at each operator's position. In the upper right hand corner of Fig. 1 there is represented a called telephone line while the portion of Fig. 2 below the broken line represents the equipment common to the cord circuits of an operator's position.

It is believed that the present system will best be understood by describing the operations involved in establishing a telephone connection from a calling to a called telephone line.

When the calling subscriber at substation A initiates a call by removing his receiver from its switchhook, the line relay 5 is energized through the back contacts of the cutoff relay 6 over the two sides of the calling line in series. The operation of the line relay lights the lamp 7 indicating that a call is awaiting attention whereupon the operator inserts the plug P of an idle cord circuit into the jack J of the calling line. The answering supervisory relay 8 is then operated, to prevent the lighting of the answering supervisory lamp 9, in a circuit traceable from grounded battery through two of the windings of the repeating coil, winding of relay 8, the tip and ring conductors of the cord circuit and thence through the plug P and jack J over the two sides of the calling line in series.

Also when the plug P is inserted in jack J the cutoff relay 6 is operated to disconnect the line relay 5 from the control of the calling line whereupon the line lamp 7 is extinguished. The energized circuit of the cutoff relay 6 extends from ground, winding of this relay, sleeve contacts of the jack J and plug P, sleeve conductor 10, winding of the sleeve relay 11 to grounded battery. The relay 11 is likewise operated over the circuit just described and effects the energization of the automatic listening relay 12 which connects the operator's telephone set (not shown) over the conductors 13 to the answering end of the cord circuit taken for use. The energizing circuit for the listen-

ing relay 12 is completed from grounded battery, inner armature and front contact of sleeve relay 11, conductor 14, winding of the relay 12, conductor 15, uppermost continuity spring and contact of relay 16, conductor 17, to ground at the lower armature and contact of relay 18. The operator now inquires for the number of the wanted line which is assumed to be the line terminating 5 at the substation B and then tests for the busy or idle condition of this line by touching the tip of the plug P' to the jack J'. Since the sleeve of this line is connected to battery when the line is busy, this busy condition is indicated by a distinctive click in 10 the operator's headset when the tip of the plug P' touches the sleeve of the jack J'. If, however, the line is idle at the time of making such a test, the operator hears no 15 click indicating that the call may be completed she inserts the plug P' into the jack J'.

As soon as the plug P' engages the jack J' the sleeve relay 19 is energized from 20 grounded battery, winding of this relay, sleeve contacts of plug P' and jack J', winding of the called line cutoff relay 20 to ground. The operation of the relay 19 closes a circuit from grounded battery, its uppermost armature and front contact, conductor 21, inner, back contact and armature of relay 18, conductor 22, winding of relay 23, to ground, causing the operation of this last named relay. The operator now depresses 25 the ringing key 24 which results in the operation of the relay 25 from grounded battery, winding of this relay, ringing key contacts 24 to ground. With the relays 23 and 25 energized, an operating circuit is completed for the relay 26 from grounded battery, winding of this relay, front contact and armature of relay 25, inner, lower front contact and armature of relay 23 to ground. The ringing relay 28 is now energized from 30 ground at the lowermost back contact and armature of relay 29, conductor 30, armature and back contact of trip relay 31, winding of relay 28, conductor 32, front contact and armature of relay 12, conductor 34, lowermost armature and front contact of relay 23, front contact and armature of relay 26, through the resistance unit to grounded battery. Relay 28 when thus operated closes a locking circuit for itself from grounded 35 battery, inner armature and front contact of relay 19, conductor 35, back contact and upper armature of relay 16, conductor 36, armature, front contact, and winding of relay 28 and thence to ground at the armature and back contact of relay 29 over conductor 30. Relays 23 and 26 in turn effect the operation of the relay 27 from grounded battery, winding of this relay, inner front contacts and armatures of relays 26 and 23 40 to ground. The relay 27 is sluggish in at-

tracting its armature in order to insure the energization of the ringing relay 28 before the operation of the relay 18 which last named relay is effective to effect the release of relay 12 which in turn disconnects the 45 operator's telephone set from the cord circuit now in use. The energizing circuit of relay 18 extends from grounded battery, inner armature and front contact of relay 19, conductor 35, winding of the relay 18, front contact and upper armature of relay 12, conductor 37, inner, upper, back contact and armature of relay 38, front contact and armature of relay 27, to ground. Relay 18 when thus energized closes a locking circuit 50 for itself from ground, through its own continuity spring and contact 39 and its own winding, and thence to grounded battery, over conductor 35 as previously described. The relay 18 at its lowermost armature and back contact opens the holding circuit of the automatic listening relay 12 which deenergizes and disconnects the operator's telephone set from this cord circuit. At the innermost, upper armature and back contact of relay 18, the energizing circuit of the relay 23 in the common key circuit is opened causing the relays 25, 26 and 27 to deenergize thereby permitting the common key equipment to revert to use on other cord 55 circuits.

As soon as the ringing relay 28 is energized, ringing current is supplied to the called line from the ringing current source, upper winding of the trip relay 31, lower, back contacts and armatures of relays 70 and 71, innermost front contact and lower armature of relay 18, lower front contact and armature of relay 28, ring contacts of plug P' and jack J' thence over the called line and through the ringer at substation B, over the upper side of the called line, tip contacts of the jack J' and plug P', uppermost front contact and armature of relay 28 to ground at the uppermost back contact 60 and armature of relay 71. Ringing current is supplied over this circuit until the called party responds at which time the trip relay 31 is operated and at its armature and back contact interrupts the locking circuit for the ringing relay 28 which deenergizes and closes the break points which existed in the talking leads of the cord circuit so that the calling and called substations are now connected over a conversational circuit. 65

The present system is equipped with party line ringing whereby any one of four substations on a telephone line may be selectively signalled. In order to select ringing current of the proper frequency to signal a wanted station on a party line, four ringing keys 24, 74, 75 and 76 are provided for the common use with all of the cord circuits of an operator's position. It has previously been described that when the ringing key 70

24 is depressed proper ringing current to signal the substation B having designation W, is applied to the called line. In the event that it is desired to signal another subscriber on this line whose designation 5 may be R the ringing key 74 is depressed which results in the operation of the relay 77. This effects the energization of the ringing current selecting relay 70 in a circuit 10 traceable from ground, upper armature and front contact of relay 77, conductor 78, lower armature and front contact of relay 12, winding of relay 70, conductor 79, conductor 35, inner, front contact and armature of relay 19 to grounded battery. Relay 70 when thus energized locks itself 15 operated from ground at the back contact and armature of relay 29, conductor 30, armature and back contact of relay 31, conductor 20 80, front contact, armature and winding of relay 70 thence to grounded battery over conductor 79 as previously described. In the event that the operator desires to signal a called subscriber whose designation may be 25 J, ringing key 75 is depressed to operate relay 81. This results in the energization and subsequent locking of relay 71 over circuits similar to those just described for the relay 70. If, however, it is desired to signal 30 the called party whose designation may be M, ringing key 76 is depressed to operate the relay 82. This in turn results in the energization and subsequent locking of both ringing selective relays 70 and 71. The operated or non-operated condition of relays 35 70 and 71 determines the character of ringing current which is applied through the trip relay 31 to the called line.

If the wanted subscriber's line terminates 40 in another exchange, the operator inserts the plug P' into the jack J2 of a trunk leading to that exchange where the call may be completed by a second operator. The originating operator then depresses the trunk key 40 which is effective to operate the relay 41. On the operation of this relay a circuit 45 is closed from ground, its lower armature and front contact, conductor 37, armature and front contact of relay 12, winding of relay 18, conductor 35, inner front contact and armature of sleeve relay 19, to ground. As indicated in the case of a local call, the 50 relay 18 effects the deenergization of the relay 12 which in turn disconnects the operator's telephone set from the cord circuit just taken for use. In the case of such a trunk call the ringing relay 28 is not operated and consequently no ringing current is transmitted over the selected trunk.

55 The present system is provided with an arrangement whereby completed calls may be charged to a calling subscriber. As soon as the call has proceeded to the point where the relay 19 operates the slow releasing relay 42 is energized in a circuit from ground-

ed battery, uppermost armature and front contact of relay 11, winding of relay 42, middle armature and front contact of relay 18, upper armature and back contact of relay 44, conductor 30, lower armature and back contact of relay 29, to ground. When the call has proceeded to the point where the calling supervisory relay 46 is energized on the response of the called party, a circuit 70 is extended from ground, armature and front contact of relay 46, conductor 48, winding of relay 44, conductor 35, inner, front contact and armature of relay 19, to grounded battery. Relay 44 is energized 75 in this circuit and effects the operation of relay 43 in a circuit traceable from ground-ed battery, winding of the relay, lowermost front contact and armature of relay 44, armature and front contact of relay 42 to ground. When the relay 43 operates, it 80 completes at its lower armature and front contact an energizing circuit for the slow operating relay 45. The metering circuit is now closed from a source of high potential 85 current (not shown) over conductor 49 through the upper armature and front contacts of relay 43, thence over the sleeve conductor 10, the sleeve contacts of plug P and jack J to the message register 72 associated 90 with the calling line. When the relay 45 operates, it opens the energizing circuit of the relay 42 which thereupon releases to open the circuit of the relay 43 which in turn breaks the metering circuit just described so that the calling line meter is 95 operated, once and once only, over the metering circuit 49, on the completion of each call.

If, however, a call should not be charged 100 to the calling substation, the non-register key 83 is depressed. This results in the operation of the relay 44 into a circuit extending from ground, closed contacts of key 83, conductor 84, lower armature and front contact of relay 12, conductors 85 and 48, winding of relay 44, conductor 35, front contact and armature of relay 19 to ground-ed battery. Under the non-register condition, the relay 44 operates to prevent the 110 energization of relay 42 in Fig. 1 so that it is impossible to complete the metering circuit and consequently metering current is not applied to the sleeve circuit 10 of the calling line.

If the calling subscriber desires to regain 115 the attention of the operator before either of the plugs P and P' have been withdrawn from the jacks with which they have been in engagement he slowly moves his switch-hook up and down one or more times to momentarily effect the release of the relay 8. As soon as this takes place the flashing recall relay 29 is operated from grounded 125 battery, uppermost armature and contact of 130

relay 11, back contact and armature of relay 8, through the resistance unit, back contact, continuity spring and winding of the relay 29, conductor 50, uppermost front contact and armature of relay 18, normally closed contacts of the listening key 51 to ground. The relay 29 as soon as it is operated closes a locking circuit for itself from grounded battery, its uppermost armature, front contact and winding and thence to ground over conductor 50 as previously described. Also when relay 29 is operated the lamp 9 associated with the calling line is intermittently lighted in the following manner. An energizing circuit is closed for the lamp 9 from grounded battery, armature and front contact of relay 29, through the resistance unit, lamp 9, front contact and armature of relay 11, to ground. Also at 20 the inner armature and front contact of relay 29, a circuit is closed from grounded battery, through the resistance units in series, armature and front contact of relay 8, inner armature and front contact of relay 25 29, back contact and continuity spring of relay 53, lower winding of relay 54 to ground. This last described circuit shunts the lamp 9 but energizes the relay 54 which closes a circuit over conductor 55, from the 30 interrupter (not shown), front contact and armature of relay 54, winding of relay 53 to grounded battery. The relay 53 is intermittently operated in accordance with the adjustment of the interrupter and on each 35 operation of this relay at its back contact and continuity spring it interrupts the conductor which has been short circuiting the lamp 9 permitting it to operate. During the time that the relay 53 is operated the relay 40 54 is held operated through both of its windings in series but when relay 53 deenergizes relay 54 is held operated through its lower winding.

In the past it has been the practice on 45 local calls when a line tested busy to insert the answering plug such as P' of the cord circuit taken for use into a busyback jack through which an interrupted busy tone was supplied over this cord circuit to the calling 50 line. In the case of such a busy call the operator's time was unnecessarily taken up in plugging into the busyback jack and subsequently taking down that connection. In 55 accordance with the present invention it is proposed to provide a busyback key 57 which is common to all of the cord circuits at an operator's position so that when a called line tests busy it is only necessary 60 for the operator to depress the busyback key momentarily after which the busy tone is transmitted to the calling line until the subscriber hangs up or until the answering plug is withdrawn from the calling jack, or until 65 the operator subsequently tests the busy line,

finds it idle and completes the connection thereto.

The depression of the busyback key 57 effects the energization of the slow releasing relay 38 from grounded battery, winding of this relay, contacts of the key 57, back contact and armature of relay 28 to ground. As soon as relay 38 operates, at its lowermost front contact and armature, it completes an energizing circuit for the slow operating circuit 27. The operation of the relays 27 and 38 complete a circuit from ground, armature and front contact of relay 27, middle armature and front contact of relay 38, conductor 58, armature and front contact of relay 12, winding of relay 16, innermost front contact and armature of sleeve relay 11 to grounded battery. Relay 16 when operated closes a locking circuit for itself from grounded battery, inner armature and front contact of relay 11, winding of relay 16, its innermost lower front contact and armature, conductor 59, contacts of the manual listening key 51 to ground. At the back contact and continuity spring of relay 16 the energizing circuit of the automatic listening relay 12 is opened, permitting this relay to deenergize so that the operator's telephone set may be used in connection with other cord circuits. Before relay 12 releases the ringing relay 28 is operated from ground at the back contact and armature of relay 29, conductor 30, armature and back contact of trip relay 31, winding of the ringing relay 28, conductor 32, front contact and armature of relay 12, conductor 34, uppermost armature and front contact of relay 38 through the resistance unit to grounded battery. On the operation of the relay 28, it locks itself energized from grounded battery, inner armature and front contact of relay 11, front contact and armature of relay 16, conductor 36, armature, front contact and armature of relay 28, and thence to ground over conductor 38 as previously described.

It will be noted that although the ringing relay 28 is energized, the ringing current is ineffective since the plug P' is not inserted into the jack of the called line but instead busy tone current is supplied from the source BZ over conductor 60, lowermost front contact and armature of relay 16, inner, back contact and armature of relay 18, lower, front contact and armature of ringing relay 28 and thence over the lower side of a portion of the cord circuit, and the lower right hand winding of the repeating coil, to grounded battery. This tone is repeated to the calling subscriber's line until the subscriber replaces his receiver on its switchhook at which time the answering supervisory relay 8 is released to give the disconnect signal. This signal is given by the lighting of the lamp 9 from grounded bat-

tery, upper armature and front contact of relay 11, back contact and armature of relay 8, through the resistance unit to the lamp 9, lower front contact and armature of relay 5 11, to ground. On noting this signal the operator removes the plug P from the jack J which results in the deenergization of the cutoff relay 6 and the sleeve relay 11. On the release of the sleeve relay 11, all of the 10 relays of the cord circuit including relay 16 and ringing relay 28 are restored to normal. It will be noted that the circuit of the ringing relay 28 while being used to control the transmission of the busyback signal, is completed at the lowermost armature and back contact of the flash recall relay 29 so that if the calling subscriber elects to initiate another call he may signal the operator 15 as in the case of an ordinary recall by moving his switchbook up and down to effect the operation of the flash recall 29 which in turn disconnects the busy tone.

It will be understood that the present disclosure is merely typical of one form of the 25 present invention and there may be many variations and modifications thereof within the scope of the claims without departing from the inventive idea.

What I claim is:

30 1. In a telephone system, a telephone exchange, telephone lines terminating at said exchange, a plurality of cord circuits, at said exchange, means including one of said cord circuits for interconnecting one of said 35 telephone lines as a calling line and another of said telephone lines as a called line, means for characterizing said telephone lines as busy or idle, a source of busy tone, and means including a busy back key common to said 40 cord circuits for transmitting a busy tone to a calling telephone line when the called telephone line is busy.

2. In a telephone system, a telephone switchboard, telephone lines terminating at 45 said switchboard, a plurality of cord circuits at each switchboard, any one of which cord circuits may be used for interconnecting one of said telephone lines as a calling line and another of said telephone lines as a 50 called line, means for characterizing any telephone line as busy or idle, a source of busy tone, and means including a busy back key common to said cord circuits for controlling the transmission of a busy tone to said 55 calling telephone line when said called telephone line is busy.

3. In a telephone system, a telephone exchange, telephone lines, means including a cord circuit for interconnecting said 60 telephone lines, a source of ringing current for signalling said telephone lines, a source of busy tone, a ringing relay in such cord circuit for controlling the application of said 65 ringing current to a called telephone line, and means including said ringing relay for

connecting said busy tone to said calling telephone line when the called line is busy.

4. In a telephone system, a telephone exchange, a calling telephone line and a plurality of called party telephone lines terminating at said exchange, a plurality of cord circuits any one of which may be used for interconnecting said calling telephone line and a called telephone line, a plurality of sources of ringing current for selectively 70 signalling any one of the parties on a called telephone line, a source of busy tone, a ringing key for each source of ringing current common to said cord circuits, said ringing 75 keys serving to control the selection of the proper source of ringing current to signal a desired party on a called line, a source of busy tone, and a busy back key common to said cord circuits for controlling the connection of said busy tone to said calling 80 telephone line when a called line is busy.

5. In a telephone system, a calling telephone line, a plurality of called telephone lines, a plurality of cord circuits, any one of which may be used for interconnecting said 85 calling telephone line and a desired called telephone line, means including a recall relay for signalling when said calling telephone line initiates a recall, a source of ringing current, a ringing relay in each cord circuit for controlling the connection of ringing current to a called telephone line, a source of busy tone, a busy back key, means including said ringing relay for connecting 90 said tone to a calling telephone line, and a circuit for said ringing relay controlled by 95 said flash recall relay and by said busy back key.

6. In a telephone system, a calling telephone line, called telephone lines, a plurality 100 of cord circuits, any one of which may be used for interconnecting said telephone lines, an operator's telephone set, automatic listening means responsive to the extension of a cord circuit to said calling telephone line 105 for connecting said operator's telephone set to said cord circuit, means responsive to the completion of the extension of the call through said cord circuit to the called telephone line for disconnecting said operator's 110 telephone set from said cord circuit, a source of busy tone, a relay for connecting said source of busy tone to a calling line, means including a busy back key and said automatic listening means serving to control the 115 operation of said relay, and means independent of said automatic listening means for maintaining said relay operated.

7. In a telephone system, telephone lines, 120 a plurality of cord circuits, any one of which may be used for interconnecting said telephone lines, an operator's telephone set, an automatic listening relay operated responsive to the extension of a cord circuit to a 125

calling telephone line, said automatic listening relay serving to connect said operator's telephone set to said cord circuit, a source of busy tone, a busy back key and a slow releasing relay controlled thereby common to said cord circuits, a relay for connecting said source of busy tone to said calling line, and means including said automatic listening relay and said slow releasing relay serving to control the operation of said relay.

8. In a telephone system, a calling telephone line, a called telephone line, a plurality of cord circuits any one of which may be used for interconnecting said telephone lines, an operator's telephone set, an automatic listening relay responsive to the extension of a cord circuit to said calling telephone line for connecting said operator's telephone set to said cord circuit, a source of busy tone, a busy tone relay for connecting said source of busy tone to a calling line, a busy back key and a slow releasing relay controlled thereby common to said cord circuits, and a circuit for said busy tone relay controlled at front contacts of said automatic listening relay and said slow releasing relay.

9. In a telephone system, telephone lines, a plurality of cord circuits, any one of which may be used for interconnecting a calling telephone line and any one of the other telephone lines, means including a recall relay for signalling when said calling telephone line initiates a recall, an operator's telephone set, an automatic listening relay responsive to the extension of a cord circuit to a telephone line for connecting said operator's telephone set to said cord circuit, a source of busy tone, a busy back key and a slow releasing relay controlled thereby common to said cord circuits, a relay for connecting said source of busy tone to said calling line, and an operating circuit for said relay controlled at contacts of said previously mentioned relays.

10. In a telephone system, a calling telephone line, a plurality of called telephone lines, a plurality of cord circuits, any one of which may be used for interconnecting said calling telephone line and any one of said called telephone lines, means including a recall relay for signalling when said calling telephone line initiates a recall, an operator's telephone set, an automatic listening relay responsive to the extension of a cord circuit to a telephone line for connecting said operator's telephone set to said cord circuit, a source of busy tone, a busy back key and a slow releasing relay controlled thereby common to said cord circuits a relay for connecting said source of busy tone to said calling line, an operating circuit for said relay controlled at contacts of said previously mentioned relays, and a locking circuit for said busy tone relay independent of said

slow releasing relay and said automatic listening relay.

In witness whereof, I hereunto subscribe my name this 2nd day of May A. D. 1930.
